UNITED STATES PATENT OFFICE.

ADAM KREUTER, OF CHICAGO, ILLINOIS.

MANGLE.

SPECIFICATION forming part of Letters Patent No. 643,189, dated February 13, 1900.

Application filed March 4, 1899. Serial No. 707,768. (No model.)

To all whom it may concern:

Be it known that I, ADAM KREUTER, a citizen of the United States of America, and a resident of Chicago, county of Cook, and State 5 of Illinois, have invented certain new and useful Improvements in Mangles, of which the following is a specification, and which are illustrated in the accompanying drawings, forming a part hereof.

10 My invention relates to that type of machines of the class named in which a padded cylinder is employed in conjunction with steam-chests, garments to be ironed being passed between the cylinder and the faces of

15 the steam-chests; and the objects of the invention are to improve machines of this type by providing the steam-chests with suitable supports by which they may be adjustably held in proper relation with the cylinder and

20 to provide improved means for bringing the steam-chests into action.

A further object is to provide means for drying the fabric with which the cylinder is covered.

25 These several objects are attained in the construction hereinafter fully described, and which is illustrated in the accompanying drawings, in which—

Figure 1 is a side elevation of the machine, 30 partly in vertical central section. Fig. 2 is a detail section on the line 2 2 of Fig. 1. Fig. 3 is a detail section on the line 3 3 of Fig. 1. Fig. 4 is a transverse vertical section on the line 4 4 of Fig. 1, and Fig. 5 is a detail of a 35 joint used in the machine.

The machine, generally speaking, comprises a frame upon which is journaled a cylinder, as B, a pair of segmental steam-chests H K being mounted concentrically with the cylinder and supported upon sliding bearings, upon which they may advance toward or be withdrawn from the cylinder, suitable levers being provided for controlling such movements. The frame comprises the two end

45 standards A A and the side rails a, uniting these standards. At their upper ends the standards are provided with suitable boxes, upon which is journaled a shaft C, upon which is fixed a cylinder B, which is made of sheet- 50 steel, freely perforated, and supported by the spiders b, fixed upon the shaft. The cylinder B is enveloped in a textile or felt pad b'.

Power is applied to rotate the cylinder by means of a belt-pulley D, fixed upon a shaft d, journaled longitudinally as to and extending the entire length of the frame and carrying pinions d', one adjacent to each end, which pinions d' intermesh with gear-wheels E, which are mounted upon shafts e, projecting outwardly from the standards A, the hub 55 of the gear-wheel E being prolonged and comprising a pinion e', which intermeshes with the gear-wheel F, fixed upon the shaft C. This train of gears is in duplicate, one at each end of the machine, in order that the strain may 60 be more evenly applied.

A steam-coil is located within the cylinder B and, as shown, comprises a plurality of longitudinally-disposed steam-pipes G, one between each pair of spokes of the spiders b. 70 Steam is served to this system of piping through a steam-pipe c, which may be located at either end of the machine and which enters a suitable longitudinal aperture formed in the end of the shaft C, a stuffing-box c' 75 being applied to the end of the shaft in order to make a steam-tight joint, while permitting the shaft to rotate relatively as to the pipe c. Connection is made between the tubular portion of the shaft C and one of the 80 steam-pipes G, as shown at g, and at its farther end this steam-pipe G is united with one of the adjacent pipes of the same character, as shown at g', which in turn is similarly united at its farther end to its next neighbor, 85 this series of connections being continued so as to connect the entire system of tubing and the last pipe G being connected with a suitable longitudinal aperture in the end of the shaft C opposite to that at which the steam 90 enters, which aperture in turn is connected with the discharge-pipe c' in the same manner as the connection is formed with the pipe c. The cylinder B being perforated, a circulation is provided through the covering-pad 95 b', and as a result this pad is kept dry.

I believe myself to be the first to apply heat to the interior of an open-ended perforated cylinder for the purpose of drying its envelop by the direct action of the heat and by the 100 circulation of air directly stimulated thereby.

Usually machines of this type are entirely unprovided with means for drying the cylinder-envelop. I am aware that it has been

proposed to set up circulation of air through the envelop by applying suction to the interior of the cylinder; but this is inefficient, even though heat may be introduced into the 5 cylinder, for the reason that the air drawn through the envelop is necessarily comparatively cool, and hence lowers the temperature of the envelop, thereby not only checking evaporation, but robbing the steam-chest of 10 heat which should be applied directly to the goods.

The steam-chests H K, which coöperate with the cylinder, are segmental in form, their inner faces being polished for application to 15 the goods and being concentric with the cylinder B. These chests are of the same length as the cylinder. The frame of the machine is provided with suitable brackets, as P, for supporting the steam-chests, and preferably 20 the supporting-faces of these brackets are flat and in the plane of radii of the cylinder, two of such brackets for each of the chests being provided, one at each end of the machine. As usual in machines of this type, 25 one of the steam-chests, H, is set at a greater elevation than the other, K, for convenience of feed and delivery, the goods being fed to the machine from a table, as V, carried by the chest H, and discharged therefrom at the 30 upper edge of the chest K, which carries a table W, upon which they may be deposited. The lower edges of the steam-chests overlap, as shown at X, so that when they are brought up to position for service a continuous surface is presented for bearing against the goods 35 as they are carried along by the cylinder. Each of the chests is provided with coöperating brackets h k, adapted to rest and slide upon the brackets P, and for the purpose of 40 securing durability, and also for the purpose of providing for a proper adjustment of the chests relatively as to the cylinder, a shoe h' is interposed between the brackets h k and the brackets P. This shoe should be loosely 45 connected to one of the coöperating brackets. As shown, this connection is with the chest-bracket and is accomplished by the use of dowel-pins h², preferably fixed in the shoe and loosely entering suitable sockets in the 50 bracket. A pair of adjusting-screws h³ passes through the bracket with which the shoe is connected, so as to bear upon it. While I have shown the shoe as connected with the chest-bracket, it is obvious that it might be 55 connected with the frame-bracket, and in the latter event the adjusting-screws h³ will be correspondingly changed. By turning down the adjusting-screw h³ nearest to the chest it will be seen that the lower edge of the 60 chest will be thrown inwardly toward the cylinder, while the setting-up of the outer adjusting-screw will result in tilting the chest in the opposite direction, so that its upper edge will be thrown more nearly to the cylinder. 65

The details of construction for the support of the two chests being the same, I have not

deemed it necessary to describe and fully illustrate more than one.

The movement of each of the steam-chests 70 is controlled by a pair of lever-arms M O, one member of each pair being located at each end of the cylinder. These lever-arms M O are pivotally mounted upon a shaft Q, which for the sake of greater strength runs 75 the entire length of the machine, and this shaft is supported upon the frame, preferably by means of brackets q in arch form, supported by the side rails a. The connection between the lever-arms M O and the steam-chests being identical in form, I have shown 80 in detail only one. The arm M is pivoted to lugs m' m', formed upon the outer face of the chest H. As the end of the arm M oscillates with a shaft Q as a center, while the movement of the chest H is a reciprocation upon a right line, in the construction shown compensation for the diverging of the paths of the two parts is provided for by making the aperture in one of the parts larger than the 85 pivot-pin m², which unites the arm M with the lugs m'. This lost motion does not interfere with the proper action of the machine, while fully serving the purpose in view. Each 90 of the lever-arms M O has a downwardly-projecting arm m o, and between them there is located a cam R, mounted upon a shaft r, journaled in the standards A A and controlled by means of a hand-lever S. When the cams R are turned to spread the arms m o, the steam-chests H K are forced toward the cylinder B. A segmental ratchet U is fixed 95 upon the shaft r, and with it coöperates a gravity-pawl u, which prevents the recession of the parts when the steam-chests are advanced toward the cylinder. Upon the release of the pawl u and the throwing back of the cam R the steam-chests fall away 100 from the cylinder, their supporting-brackets being inclined downwardly at their outer 105 ends.

It is necessary in machines of this character that the polishing-surfaces be held to the cylinder by yielding supports, and this is provided for by setting transversely through each 110 of the arms m o a reciprocating flat-headed bolt T, against the head of which the cam R bears, and encircling the stem of the bolt with a coil-spring t, the aperture provided for the bolt being counterbored to accommodate the spring. As thus constructed the parts of the machine may be easily adjusted and always kept in proper relation, any wear of the bearing parts being easily compensated for by a readjustment by means of the screws h³. 115

The chests H K are supplied with steam by means of a pair of pipes Z, leading one to each of the chests and being capable of sufficient oscillation to permit of the movement of the chests in the manner described. 120

I claim as my invention—

1. In a mangle, the combination with a suitable frame, and a revolving cylinder journaled thereon, of a segmental steam-chest car-

ried directly by the frame and having its inner face concentric with the cylinder, brackets carried by the frame for supporting the chest, brackets fixed to the chest and adapted to slide upon the supporting-brackets and to hold the chest against pivotal movement; and means for moving the chest upon its supports to and from the cylinder.

2. In a mangle, the combination with a suitable frame, and a revolving cylinder journaled thereon, of a pair of segmental steam-chests having their inner faces concentric with the cylinder, brackets carried by the frame for supporting the chests, brackets secured to the chests and adapted to slide upon the supporting-brackets, and means for moving the chests upon their supports to and from the cylinder.

3. In a mangle, the combination with a suitable frame, and a revolving cylinder journaled thereon, of a segmental steam-chest having its inner face concentric with the cylinder, brackets carried by the frame for supporting the chest, brackets secured to the chest and adapted to slide upon the supporting-brackets, a lever-arm pivotally carried by the frame and engaging the chest to move it on its supports, a cam for actuating the lever-arm, and means for controlling the cam.

4. In a mangle, the combination with a suitable frame, and a revolving cylinder journaled thereon, of a pair of segmental steam-chests having their inner faces concentric with the cylinder, brackets carried by the frame for supporting the chests, brackets secured to the chests and adapted to slide upon the supporting-brackets, means for moving the chests upon their supports to and from the cylinder, a lever-arm pivotally carried by the frame and engaging the chests to move them on their supports, a cam for actuating the lever-arm, and means for controlling the cam.

5. In a mangle, the combination with a suitable frame, and a revolving cylinder journaled thereon, of a segmental steam-chest having its inner face concentric with the cylinder, brackets carried by the frame for supporting the chest, brackets secured to the chest and adapted to slide upon the supporting-brackets, shoes for such chest-brackets and loosely secured thereto, adjusting-screws setting through the chest-brackets and bearing upon the shoes, and means for moving the chest upon its supports to and from the cylinder.

6. In a mangle, the combination with a suit-

able frame, and a revolving cylinder journaled thereon, of a segmental steam-chest having its inner face concentric with the cylinder, brackets carried by the frame for supporting the chest, brackets secured to the chest and adapted to slide upon the supporting-brackets, a shoe interposed between each pair of coöperating frame and chest brackets and loosely secured to one of such members, adjusting-screws bearing upon the backs of such shoes for adjusting the chests relatively as to the cylinder, and means for moving the chest upon its supports to and from the cylinder.

7. In a mangle, in combination, frame; a cylinder journaled on the frame; a pair of segmental steam-chests concentric with the cylinder; sliding bearings for the chests, radial as to the cylinder; a pair of lever-arms, one at each end of the frame, for advancing each chest to the cylinder, the power ends of the levers projecting downwardly; a cam for spreading the lower ends of the lever-arms at each end of the frame; a rock-shaft for carrying both cams; a ratchet and pawl for holding the shaft; and a hand-lever for rocking the shaft.

8. In a mangle, the combination with a revolving perforated cylinder having its ends open for the free admission of air and being covered with textile or felt fabric, a system of steam-pipes within the cylinder, connections whereby the pipes may be served with steam, and segmental steam-chests having polished ironing-faces for coöperating with the surface of the cylinder.

9. In a mangle, in combination, a frame; a shaft journaled on the frame, and being tubular at its ends; a perforated cylinder carried by the shaft and having its ends open for the free admission of air and a textile or felt covering; a plurality of pipes located within the cylinder and arranged longitudinally thereto, two of such pipes being connected respectively with the opposite tubular ends of the shaft, and the several pipes being connected to form a continuous circulating system; steam-pipes connected with the shaft ends, and being rotatable relatively thereto; and segmental steam-chests having polished ironing-surfaces for coöperating with the surface of the cylinder.
